UNITED STATES PATENT OFFICE.

EDWARD BERNARD HESS AND LEWIS CARY MYERS, OF BROOKLYN, NEW YORK.
ASSIGNORS TO ROYAL TYPEWRITER COMPANY, INC., OF NEW YORK, N. Y.

LINE-LOCK MECHANISM AND MARGIN-RELEASE MECHANISM FOR TYPEWRITING MACHINES.

1,417,906.

Specification of Letters Patent. Patented May 30, 1922.

Original application filed January 13, 1921, Serial No. 436,924. Divided and this application filed May 27, 1921. Serial No. 473,167.

To all whom it may concern:

Be it known that we, EDWARD BERNARD HESS and LEWIS CARY MYERS, both citizens of the United States, residing in Brooklyn, county of Kings, city and State of New York, have invented certain new and useful Improvements in Line-Lock Mechanism and Margin-Release Mechanism for Typewriting Machines, of which the following is a specification.

This invention relates to line lock mechanism and margin release mechanism for typewriting machines in which the universal bar, by which the escapement mechanism is operated, is locked or held fixed when the end of a printed line is reached and it also relates to mechanism whereby the typewriter carriage may be released after being arrested by a margin stop so that one or more additional characters may be printed.

In our application for patent filed Jan. 13, 1921, No. 436,924, of which this application is a division, we have shown such mechanism embodied in a typewriting machine of the Royal type but of such construction as to provide a small, compact and light machine having the essential features of the larger or standard Royal machine but which is portable and may be made and sold at a relatively low cost.

Our present improvements may, however, be embodied in machines whether portable or otherwise.

According to our invention a margin stop lever is mounted centrally in rear of the margin stop rail and it is provided with an arm extending laterally to one side of the machine where it is connected by a link with a margin release key made of sheet metal, its finger-piece being located just above the upper banks of keys in the keyboard and its movement in opposite directions being controlled by stops formed integrally with it. A vertically arranged line lock lever mounted in the central portion of the rear part of the machine is pivotally connected with the margin stop lever and it is operated by a margin stop, when the end of a line, controlled by a margin stop, is reached. The line lock lever is controlled by an arm projecting from the universal bar which, as usual, is operated by the key levers and space key and which operates the escape-

ment mechanism. Normally the line lock lever is out of the path of the line lock arm 55 of the universal bar, but when the end of a line is reached the line lock lever is so moved as to bring its lower end into the path of said arm and prevent its movement so as to arrest the movement of the universal bar and thus lock the type lever and prevent further printing.

In the accompanying drawings:—

Figure 1 shows a vertical section of so much of a typewriting machine with our 65 improvements applied as is necessary to illustrate our invention.

Figures 2 and 3 are detail views of the escapement mechanism in connection with which the line lock mechanism and the margin release mechanism are employed.

Figure 4 is a view, on an enlarged scale, showing how the margin stop lever and the line lock lever are mounted centrally in the rear portion of the machine.

A part of the frame of a typewriting machine is indicated at A. The platen is shown at B, and its carriage at C. The carriage rack-bar D cooperates with a pinion E on a shaft F, carrying a ratchet wheel G. The escapement rocker H is equipped with a roller-carrying dog I and a limber dog J. An adjustable roller-carrying spring arm K is operated by a lever L, arranged centrally in rear of the rocker and which is connected 85 by a link M with the arm m of the universal bar N which comprises a shaft n, two side pieces n' which turn about the axis of the bar N, and a rear cross-piece n''. An arm O extends rearwardly from the universal 90 bar and cooperates with the line lock lever in the manner hereinafter described.

One of the type key levers is indicated at P. When a key is depressed the rear portion of the universal bar is raised, and by 95 means of the link M the lever L is actuated to operate the escapement. This mechanism is further illustrated in our application for patent above mentioned and is more fully described therein.

The margin stop lever Q is pivotally connected at q to a reinforcing plate R attached to the rear portion of the frame and it cooperates with a margin stop S on a margin stop rail S'. The lever Q has a laterally extending arm q' which projects to near the

right-hand side of the machine and is connected by a link q^2 with a margin stop lever q^3 by means of which the margin stop lever may be moved out of the path of the margin stop. The margin release key q^3 is located at the right hand side of the machine above the keyboard, being pivoted to a rod Q^2 on which the front links of the type bar actuating mechanism is supported. The key is made of sheet metal, its finger-piece being located just above the upper bank of keys within easy reach of the operator. Its movements in opposite directions are controlled by an arm q^4 provided with stops q^5 , q^6 and its inner end q^7 , which is bent upwards, is connected to a link q^2 . The rear end of the link q^2 is connected with the arm q^4 . It will be observed that normally the margin stop lever at its upper end is in the path of the margin stop S ; that when a margin stop approaches the lever a bell is rung and immediately thereafter the movement of the carriage is arrested but when the key q^3 is operated the upper end of the lever Q is moved backward and thereby removed from the path of the margin stop. This operation is similar to that of other Royal machines.

The line lock lever T is pivotally connected with the front side of the margin stop lever at t . Its upper portion extends along the right-hand side of the margin stop lever in the path of the right-hand margin stop S . From its pivot it extends downwards and its lower end is normally held away from the line lock arm O by a spring t' , its return movement being limited by a stop t^2 which engages the lever Q .

When the end of a line, determined by the position of the margin stop, is reached the line lock lever is swung on its pivot in such manner as to move its lower end into the path of the arm O of the universal bar so that the universal bar cannot be operated and hence the key levers and type bars are held fixed and the escapement mechanism cannot be moved.

The mechanism is extremely simple but has been found in practice to be very efficient.

We claim as our invention:

1. In a typewriting machine, pivoted key levers, a carriage, escapement mechanism therefor, a universal bar pivotally mounted in rear of the pivots of the key levers for operating the escapement mechanism and which is provided with a rearwardly extending, vertically moving line lock arm, and a line lock lever engaged by the carriage and operating upon the line lock arm of the universal bar.

2. In a typewriting machine, a carriage, escapement mechanism therefor, a universal bar for operating the escapement and which is provided with a line lock arm, a margin

stop lever, a margin stop mounted on the carriage which engages the margin stop lever, and a line lock lever pivoted to the margin stop lever and adapted to engage the arm of the universal bar. 70

3. In a typewriting machine pivoted key levers, a universal bar pivotally mounted in rear of the pivots of the key levers having a centrally arranged rearwardly projecting vertically moving line lock arm, a line lock lever pivoted to move about a horizontal axis parallel with the longitudinal axis of the machine, means for normally holding the line lock lever out of engagement with the line lock arm of the universal bar, and means 80 for actuating the line lock lever to move its lower end into the path of the line lock arm when the end of a line is reached.

4. In a typewriting machine the combination of a universal bar having a rearwardly 85 projecting line lock arm, escapement mechanism operated by the universal bar, a margin stop lever mounted in rear of the escapement mechanism, a margin stop adapted to engage the margin stop lever, and a line lock 90 lever pivotally connected with the margin stop lever normally held out of the path of the line lock arm of the universal bar but adapted to move into the path thereof and hold the universal bar out of operation when 95 the end of a line is reached.

5. In a typewriting machine, a carriage, escapement mechanism therefor, a universal bar for operating the escapement and which is provided with a line lock arm, a pivoted 100 margin stop lever, a line lock lever pivoted to the margin stop lever and a margin stop which engages the line lock lever and moves it into engagement with said line lock arm, thereby locking the universal bar against 105 movement.

6. In a typewriting machine, a carriage, escapement mechanism therefor, a universal bar for operating the escapement and which is provided with a line lock arm, a pivoted 110 margin stop lever, a line lock lever movably carried thereby, a margin stop which engages the line lock lever and moves it into position to lock the universal bar against movement, and means for moving the margin stop lever to release said lock. 115

7. In a typewriting machine, a carriage, escapement mechanism therefor, a universal bar for operating the escapement and which is provided with a line lock member, a pivoted margin stop lever, a line lock lever pivoted on the margin stop lever, a margin stop for moving the line lock lever about its pivot to engage said member and lock the universal bar, and means for moving the margin stop lever about its pivot to release said lock. 120

8. In a typewriting machine, a carriage, a margin rail, adjustable stops thereon, margin stop mechanism cooperating with the 130

stops, a margin release key pivotally mounted on the front end of the machine and which is connected with the margin stop mechanism, said key comprising a front portion outside the machine frame, and a stop on the key which engages the machine frame.

9. In a typewriting machine, a carriage stop lever pivotally mounted at the rear of the machine and having a laterally projecting arm extending to one side of the machine, a margin release key pivotally mounted at one side of the front of the machine above the keyboard movable about a horizontal axis extending crosswise of the machine, and a connection between the margin release key and the margin stop lever.

10. In a typewriting machine a margin stop lever pivotally mounted at the rear of the machine, a margin release key pivotally

mounted at one side of the front frame of the machine above the keyboard movable about a horizontal axis crosswise of the machine and having stops for limiting its movements in both directions, and connections between the margin release key and the margin stop lever.

11. In a typewriting machine a margin stop lever mounted at the rear of the machine, a margin release key pivotally mounted at the front of the machine and having an arm provided with stops for limiting its movement in both directions and having another arm which is connected with the margin stop lever.

In testimony whereof, we have hereunto subscribed our names.

EDWARD BERNARD HESS.
LEWIS CARY MYERS.
